UNITED STATES PATENT OFFICE

WILLIAM A. HAVEN, OF YOUNGSTOWN, OHIO

BLAST-FURNACE OPERATION

Application filed April 9, 1927. Serial No. 182,312.

In blast furance operation, the materials supplied at the top progressively work down as space is gained below, chiefly by the combustion of the coke. In some instances operation may become irregular, and the column of material sticks and hangs, and difficulties are encountered which may produce serious danger, even including explosion and destruction of the furnace. Furnace operation such as to avoid tendencies to such irregularities is accordingly highly desirable.

To the accomplishment of the foregoing and related ends, the invention, then, consists of the features hereinafter fully described and particularly pointed out in the claims, the annexed drawing and the following description setting forth in detail but one of the various ways in which the principle of the invention may be applied.

In said annexed drawing:—

Fig. 1 is a side elevation, part in section, showing an embodiment of my invention; Fig. 2 is a sectional detail on enlarged scale; Fig. 3 is a section taken on a plane indicated by the line III—III, Fig. 2; and Figs. 4, 5 and 6 show various modified arrangements.

I have found that the processes going on in the active zone of a furnace in blast may be largely influenced by the character of the air current, and improved operation may be had where instead of a smoothly supplied current of air, the air stream is fluctuated in rather abrupt vibrations. Just why this should be so is not at present clear, whether by reason of an improved cleaning of the surfaces of the coke from ash films, or from improved elimination of occluded gases on the glowing coke, or from vibration assisting mechanically or chemically. I accordingly content myself here with statement of the fact without commitment as to any theory.

In accordance with my invention, I employ the tuyère T and stove system arranged as customary, and for the blast a source of air supply, and the air is caused to fluctuate or vibrate, preferably with rather sharp or abrupt vibrations. An advantageous arrangement may comprise a turbo type blower 3 driven at high speed by a suitable driving engine or motor, this producing the air blast

most efficiently from the standpoint of engineering operation, and interposed in the connection between the furnace F is a pulsator or fluctuator 5 as it may be termed. This may vary somewhat in its detail, involving essentially a means for causing a fluctuation or pulsation of the blast in waves. An advantageous construction comprises a rotor cage 6 mounted in a suitable casing 7 and having a drive shaft 6' operated by a motor or the like. The casing 7 has opposite ports 9 connecting in the line, and the rotor cage 6 also has opposite ports 10, such that as the shaft 6' and the cage 6 are rotated, the ports 10 will intermittently come in line with the ports 8 of the casing and at such instants allow of free flow of the air stream. At the other portions of the rotation cycle, however, the walls 11 having fenestrations 12 pass across the ports 8 of the casing and impart a fluctuation or vibration to the air flow.

In operating in accordance with my improvement, the furnace being charged as usual, the blast is supplied from the blower source 3, and is brought into fluctuation or vibration by the pulsator or fluctuator, and is supplied into the reaction zone of the furnace. Operation proceeds, it is found, with marked smoothness and regularity.

While usually it is preferable to locate the fluctuator between the air source and the stove, as indicated in Fig. 4, in some cases it may be located between the stove and the furnace, as in Fig. 1. In some cases also I contemplate placing it in the downcomer 17 beyond the furnace, as in Fig. 6. The advantages of the invention are generally realized in greatest degree, however, with fluctuations applied from the feed side and, for example, with a vibration rate of about 75 vibrations per minute. In Fig. 5 is shown a reciprocatory fluctuator on the pipe a which is receiving the air supply from a suitable compressor of any preferred type, not shown, the fluctuator having a cylinder 14 in communication with the pipe, and the plunger 13 being driven by an engine 15 having a valve gear 16.

Other modes of applying the principle of the invention may be employed, change being made as regards the details disclosed, pro-

vided the steps or means stated in any of the following claims, or the equivalent of such, be employed.

I therefore particularly point out and distinctly claim as my invention:—

- 5 1. The combination of a blast furnace, a tuyère, an air compressor for supplying an air blast, and means controllable to cause the blast to fluctuate regularly with a force insufficient to bodily displace the fuel bed.
- 10 2. The combination of a blast furnace, a tuyère, a rotary air compressor in communication therewith, and an independently controllable rotary fluctuator interposed between the compressor and the tuyère to produce a blast fluctuating regularly with a force insufficient to bodily displace the fuel bed.
- 15 3. In blast furnace apparatus, the combination of an air compressor, a tuyère for entry of air to the furnace, and a fluctuator between the pump and tuyère, said fluctuator including a casing, a rotary cylindrical cage therein having spaced ports for passage of the air, and means for rotating said cage.
- 20 23. Signed by me, this 7th day of April, 1927.

WILLIAM A. HAVEN.
